STEAM GENERATOR

John Phillips Badenhausen, Philadelphia, Pa., assignor of one-half to Bayard Badenhausen, Philadelphia, Pa.

Application March 30, 1945, Serial No. 585,619

5 Claims. (Cl. 122—255)

1

This invention relates to steam generators and more particularly to steam generators adapted for burning pulverized anthracite coal, anthracite culm and other fuels. It is the principal object of the present invention to provide a steam generator having improved means for introducing air for supporting combustion.

It is a further object of the present invention to provide improved apparatus for introducing air for the combustion of fuel for steam generation.

It is a further object of the present invention to provide an improved arch construction with provisions for introducing air therethrough for supporting combustion.

It is a further object of the present invention to provide apparatus for burning fuel for steam generation which will be adequately protected from the high temperature of the combustion of the fuel.

Other objects of the invention will be apparent from the specification and claims.

The nature and characteristic features of the invention will be more readily understood from the following description, taken in connection with the accompanying drawings forming part hereof, in which:

Figure 1 is a vertical transverse sectional view of a steam generator embodying the present invention taken approximately on the line 1—1 of Fig. 2;

Fig. 2 is a vertical central sectional view taken approximately on the line 2—2 of Fig. 1;

Fig. 3 is an enlarged fragmentary view partly in plan and partly in horizontal section illustrating a preferred arch construction in accordance with the present invention; and

Fig. 4 is an enlarged fragmentary sectional view taken approximately on the line 4—4 of Fig. 3.

It should of course be understood that the description and drawings herein are illustrative merely, and that various modifications and changes may be made in the structure disclosed without departing from the spirit of the invention.

Referring more particularly to the drawings, a steam generator of a particular type is illustrated for purposes of explanation of the invention. The steam generator as shown includes a vertical front wall 10, a vertical rear wall 11, and vertical side walls 12 and 13. An upper horizontal steam and water drum 14 is provided extending rearwardly from the front wall 10 with its longitudinal axis parallel to the side walls 12 and 13. At the lower part of the side wall 12 and 13, lower water headers 15 and 16 are provided extending from front to rear with their longitudinal axes parallel to the axis of the steam and water drum 14. Between the front wall 10 and the rear wall 11 an upwardly extending vertical wall or baffle 17 is provided preferably extending from the side wall 12 to the side wall 13. The upper ends of the side walls 12 and 13 are preferably connected to top wall sections 18 and 19 and a central top wall section 20, covering the drum 14, extends between the top wall sections 18 and 19.

and 13. At the lower part of the side wall 12 and 13, lower water headers 15 and 16 are provided extending from front to rear with their longitudinal axes parallel to the axis of the steam and water drum 14. Between the front wall 10 and the rear wall 11 an upwardly extending vertical wall or baffle 17 is provided preferably extending from the side wall 12 to the side wall 13. The upper ends of the side walls 12 and 13 are preferably connected to top wall sections 18 and 19 and a central top wall section 20, covering the drum 14, extends between the top wall sections 18 and 19.

The front wall 10 is preferably provided with a fuel inlet opening 21 for the introduction of fuel in any desired manner. The space to the rear of the front wall 10 in front of the wall or baffle 17 and between the side walls 12 and 13 preferably constitutes a combustion chamber. A grate 22, extending rearwardly from the front wall 10 to the wall or baffle 17, may be provided for retaining a bed of burning fuel at the lower part of the combustion chamber. The grate 22 preferably serves as a closed hearth and the space 20 below the grate 22 is preferably closed and not provided with any air supply.

The side walls 12 and 13 of the combustion chamber are preferably lined with banks of steam generating riser tubes 23 which extend upwardly along the interior of the side walls 12 and 13 from the lower water headers 15 and 16 to the steam and water drum 14.

A bank of spaced steam generating riser tubes 24 is provided, the tubes 24 extending upwardly from the headers 15 along the interior of the side wall 12 and then substantially horizontally and transversely across to the other side wall 13 then upwardly along the interior of the wall 13 and beneath the top wall section 19 to the steam and water drum 14.

A bank of spaced steam generating riser tubes 25 is provided, the tubes 25 extending upwardly from the header 16 along the interior of the side wall 13 and then substantially horizontally and transversely across to the other side wall 12 then upwardly along the interior of the wall 12 and beneath a top wall section 18 to the steam and water drum 14.

The substantially horizontal portions of the tubes 24 and 25 serve as supports for an arch 30 illustrated in more detail in Figs. 3 and 4. The arch 30 preferably consists of a plurality of I-shaped block elements 31 of refractory material. The elements 31 preferably each have a horizontal top flange or section 32, with an upper exposed

face 33, a central downwardly extending web 34, and a horizontal lower wall or flange portion 35, with a lower exposed face 36. The top sections 32 are preferably shaped at their transverse edges 37 to conform to the shape of the tubes and to rest thereon as illustrated in Fig. 4.

The block elements 31 each have edge portions 38 for engagement with corresponding edge portions 39 of adjoining block elements 31 and the lower wall portions also have transverse edge portions 39 for engagement with corresponding edge portions 39 of adjoining block elements 31.

The block elements 31 are provided with openings 40 for the downward delivery of air from interior air compartments 41. The number and sizes of the openings 40 may be varied in accordance with the air requirements for the burning of the particular fuel employed, the openings 40 being provided in sufficient number and of sufficient size to provide all the air required for the combustion of the fuel on the grate 22. Air is supplied to the compartments 41 by aid ducts 42.

It will be noted that the block elements 31, by reason of their shape, may readily be positioned on the horizontal tube portions of the banks of tubes 24 and 25 with the edge portions 37 resting on the horizontal portions of the tubes 24 and 25, and with the edge portions 38 and 39 respectively in engagement, to provide the arch construction in accordance with the present invention.

The mode of operation will, it is thought, be clear from the foregoing but it may be noted that fuel is supplied through the fuel opening 21 and delivered to and distributed on the grate 22 in any desired manner. Air is supplied for combustion through the ducts 42 to the compartments 41 and from the compartments 41 downwardly through the openings 40. The air for combustion is thus directed onto the fuel on the grate 22. The fuel burns on the grate 22 and the burning continues as the hot gases of combustion pass around the front of the arch 39 and across the top faces 33 thereof. The heat released by the combustion is effective for generating steam in the banks of wall tubes 23 and in the tubes of the banks of tubes 24 and 25. The steam rises in the tubes 23, 24 and 25 and is delivered by these tubes to the steam and water drum 14. The air moving in the compartments 41 prevents the overheating of the arch 39 at the lower wall portions 35 thereof and prevents the overheating of the top sections 32 thereof as the hot gases of combustion pass thereover.

The horizontal sections of the tubes 24 and 25, in addition to their function of generating steam, also support the arch 39 and aid in cooling the top sections 32 of the arch 39, thereby preventing the same from becoming overheated.

I claim:

1. In a steam generator, a steam and water compartment, a combustion chamber below said compartment having side walls and a bottom wall providing a hearth, steam generating tubes connected to said steam and water compartment and having substantially horizontal portions, and arch blocks carried on said portions of said tubes, said arch blocks being I-shaped and having upper portions and lower portions, the spaces between said upper and lower portions of said blocks comprising air delivery compartments, and said lower portions of said blocks being provided with openings for the discharge of air to

ward said hearth for the combustion of fuel thereon.

2. In a steam generator, a steam and water compartment, a combustion chamber below said compartment having side walls and a closed bottom wall providing a hearth, steam generating tubes connected to said steam and water compartment and having substantially horizontal portions and arch blocks carried on said portions of said tubes, said arch block being I-shaped and having upper portions in engagement with said portions of said tubes and lower portions, the spaces between said upper and lower portions of said blocks comprising air delivery compartments, and said lower portions of said blocks being provided with openings in communication with said air compartments for the discharge of air toward said hearth for the combustion of fuel thereon.

3. In a steam generator, a steam and water compartment, a combustion chamber having side walls and a bottom wall providing a hearth, steam generating tubes connected to said steam and water compartment and having substantially horizontal portions, and arch blocks carried on the horizontal portions of said tubes, said arch blocks being I-shaped and having upper portions, lower portions and webs extending between said portions of said blocks, the spaces between said upper and lower portions of said blocks and said webs comprising air delivery compartments, and said lower portions of said blocks being provided with openings for the discharge of air toward said hearth for the combustion of fuel thereon.

4. In a steam generator, a steam and water compartment, a combustion chamber below said compartment having side walls and a closed bottom wall providing a hearth, steam generating tubes connected to said steam and water compartment and having substantially horizontal portions, and arch blocks carried on the horizontal portions of said tubes, said arch blocks being I-shaped and having upper portions in engagement with said portions of said tubes, lower portions, and webs extending between said portions of said blocks, the spaces between said upper and lower portions of said blocks and said webs comprising air delivery compartments, and said lower portions of said blocks being provided with openings for the discharge of air toward said hearth for the combustion of fuel thereon.

5. In a steam generator, a steam and water compartment, a combustion chamber having side walls and a closed bottom wall providing a hearth, steam generating tubes connected to said steam and water compartment and having substantially horizontal portions, and arch blocks carried on the horizontal portions of said tubes in edgewise engagement, said arch blocks being I-shaped and having upper portions in engagement with said portions of said tubes, lower portions and webs extending between said portions, the spaces between said upper and lower portions of said blocks and said webs comprising air delivery compartments, the lower portions of said arch blocks being in edgewise engagement and provided with openings at the edges for the discharge of air toward said hearth for the combustion of fuel thereon.
